CLAIM

We claim, the ornamental design for an electric connector, as shown and described.

DESCRIPTION

FIG. 1 is a perspective view of an electric connector, showing our new design;

FIG. 2 is a front view thereof;

FIG. 3 is a rear view thereof;

FIG. 4 is a top plan view thereof;

FIG. 5 is a first side view thereof;

FIG. 6 is a bottom plan view thereof; and,

FIG. 7 is a second side view thereof, taken opposite from FIG. 5.
